UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

VACUUM PUMP.

Application filed October 19, 1921. Serial No. 508,858.

My invention relates to vacuum pumps.

It has for its object to provide an improved vacuum pump. A further object of my invention is to provide an improved 5 cooling means for such a pump wherein a constant circulation of cooling medium is maintained about the cylinder and all trapping of air or the like is eliminated. These and other advantages of my improved construction will, however, hereinafter be more 10 fully brought out.

In the accompanying drawings I have shown for purposes of illustration one embodiment which my invention may assume 15 in practice.

In these drawings,—

Fig. 1 is a central longitudinal partial sectional view of a pump cylinder constructed in accordance with this form of my invention.

Fig. 2 is a sectional view on line 2—2 of Fig. 1.

Fig. 3 is a sectional view on line 3—3 of Fig. 2.

Fig. 4 is a detail view showing the air escape passage.

In this illustrative construction I have shown a cylinder 1 having a piston 2 movable therein, the piston being adapted to be 30 reciprocated in the cylinder in a well known manner to draw an air or gas from a usual intake 3 through passages 4 and radially located valves 5 and to discharge the air or gas through radially located valves 6, passages 7, and an outlet 8.

In my improved construction it will be noted that the piston is provided with beveled edges 9 on its opposite sides and that the cylinder is provided with correspondingly shaped ends 10 while the valves 5 and 6 are disposed at an angle in heads 11 and 12 suitably connected to a central cylinder carrying member 13 in such a manner that the ends of the valves lie substantially in the 45 plane of the beveled surfaces 10 of the cylinder.

Attention is also directed to the fact that the cylinder 1 is surrounded by a suitable cooling jacket 14 receiving a cooling medium 50 from a suitable inlet pipe 15 at its bottom. From this inlet 15 the cooling medium passes up and around each side of the lower half of the cylinder, the member 16 shown in Figs. 1 and 2 being only a boss, until it 55 reaches enlarged chambers 17 which in turn

communicate through ports 18 with lateral extensions on the opposite sides of cooling chambers 19 and 20 in the cylinder heads, the chamber 20 herein extending around the piston rod. When the cooling medium enters 60 these chambers 19, 20, of which one is shown in Fig. 2, it will evidently fill the same up to the points 21 and since these points are lower than the end walls of the chambers, the cooling medium will pass out of ports 22, 65 23, into and around the upper half of the jacket 14 to an outlet or discharge pipe 24 at the top thereof, it being understood that the member 25 is a cylinder lubricating stud in no way interrupting the flow of the cooling medium and acting only to enable lubricant to be supplied from a suitable pipe 26 to a suitable passage 27 in the stud leading to the cylinder.

With the cooling medium in the chambers 19 and 20 and filling the same up to the points 21, air will evidently be trapped in the upper parts of the chambers and thereby produce a dead space incapable of being cooled by the cooling system, unless some air outlet is supplied. To eliminate this difficulty, I have provided an outlet in the form of a passage 28 leading upward from the top of each of these chambers 19 and 20 into the upper half of the jacket 14 so that any air trapped in the chambers 19 and 20 may escape into the cooling medium in the upper half of the jacket and with that cooling medium pass out through the discharge 24, the passage 28 thereafter acting 70 as a part of the circulating system.

As a result of my improvement, it will be observed that through my improved arrangement of piston, cylinder, and valves, clearance is minimized while through the use of the cooperating cooling means, all portions of the walls of the cylinder save those carrying the valves are effectually cooled by a constant circulation of the cooling medium, while any air which would otherwise be trapped in the heads is caused to pass out into the circulating stream and thereby permit circulation through all parts of the cooling system.

While I have in this application specifically described one form which my invention may assume in practice, it will be understood that this form of the same is shown for purposes of illustration and that the invention may be modified and embodied in va-

rious other forms without departing from its spirit or the scope of the appended claims.

What I claim as new and desire to secure by Letters Patent is:

1. In a pump, a cylinder, a piston therein, a plural chambered jacket surrounding said cylinder, coaxial chambers in the heads of said cylinder, and means for establishing a flow of cooling medium through said jacket and chambers including connections between one part of said jacket and said chambers and from said chambers to the other part of said jacket, and a branch passage leading from said chambers into one of the parts of said jacket.
2. In a pump, a cylinder, a piston therein, a plural chambered jacket surrounding said cylinder, coaxial chambers in the heads of said cylinder, and means for establishing a flow of cooling medium through said jacket and chambers including oppositely disposed discharge and inlet ports at the adjacent ends of the parts of said jacket and communicating with said chambers, and branch passages one leading from each of said chambers into the upper part of said jacket.
3. In a pump, a cylinder, a piston therein, a plural chambered jacket surrounding said cylinder, coaxial chambers in the heads of said cylinder, and means for establishing a flow of cooling medium through said jacket and chambers including oppositely disposed discharge and inlet ports at the adjacent ends of the parts of said jacket communicating with said chambers, and branch passages one disposed in the upper part of each of said chambers and communicating with the discharge.
4. In a pump, a cylinder, an upper and lower jacket surrounding said cylinder, chambers in the heads of said cylinder, and passages connecting both of said jackets with said chambers, said passages connecting the lower jacket with said chambers being adapted to prevent the trapping of air in said lower jacket.
5. In a pump, a cylinder, an upper and lower jacket surrounding said cylinder and each extending substantially the entire length of the latter and including a transverse partition separating the same, chambers in the heads of said cylinders, and transverse passages disposed adjacent said partition to connect said lower jacket with said chambers.
6. In a pump, a cylinder, an upper and lower jacket surrounding said cylinder, coaxially disposed chambers in the heads of said cylinder, said chambers being of reduced diameter from said jacket, and transverse passageways connecting said jackets with said chambers.
7. In a pump, a cylinder, an upper and lower jacket surrounding said cylinder in-

cluding a partition separating the same, coaxially disposed chambers in the heads of said cylinder, said chambers being of reduced diameter from said jacket, and transverse passageways connecting said jackets with said chambers, said passageways terminating at one end in said jackets adjacent said partition.

8. In a pump, a cylinder, separated jackets surrounding the same, a chamber in the head of said cylinder of smaller diameter than said jackets, and a transverse passage connecting said chamber and jackets.

9. In a pump, a cylinder, separated jackets surrounding the same, a chamber in the head of said cylinder of smaller diameter than said jackets, and a transverse passage connecting said chamber and jackets, said passage being disposed below the level which liquid within said chamber and jacket will normally assume.

10. In a pump, a cylinder, a jacket surrounding the same, a chamber in the head of said cylinder of smaller diameter than said jacket, a transverse passage connecting said chamber and jacket, said passage being disposed below the level which liquid within said chamber and jacket will normally assume, and a second passage disposed above the first mentioned passage and connecting the upper portion of said chamber with said jacket, and constituting means for preventing the trapping of air in said chamber.

11. In a pump, a cylinder, a plural chambered cooling jacket surrounding the same, a cooling chamber in the head of said cylinder and whose diameter is less than that of the cylinder jacket, and a transverse passage adapted to allow communication between the adjacent portions of the plural chambers and the chamber in said head.

12. In a pump, a cylinder, a piston reciprocable therein, a water jacket surrounding said cylinder, water chambers in the heads of said cylinder, means for connecting said jacket and chambers, and branch passages connecting said jacket and chambers.

13. In a pump, a cylinder having heads, and jacket means including a plural chambered jacket surrounding said cylinder, chambers one in each cylinder head, and means for establishing a flow of temperature controlling medium to fill completely said jacket and chambers in said heads including means providing communication between the chambers of said cylinder jacket and said chambers in the heads arranged at opposite sides of said cylinder and at opposite ends thereof, and means for preventing the trapping of air in said several chambers including branch passages connecting said chambers in said heads with said jacket for the cylinder.

In testimony whereof I affix my signature.

FRED D. HOLDSWORTH.
